US0D1114062S

(12) United States Design Patent (10) Patent No.: US D1,114,062 S
(45) Date of Patent: * Feb. 17, 2026

(54) BOOK COVER

(71) Applicant: Anne-Christine Berthier, Paris (FR)

(72) Inventor: Anne-Christine Berthier, Paris (FR)

() Term: 15 Years

(21) Appl. No.: 29/972,494

(22) Filed: Nov. 11, 2024

(30) Foreign Application Priority Data

Oct. 23, 2024 (EM) 015076940-0001

(51) LOC (15) Cl. 19-04

(52) U.S. Cl.

USPC D19/29

(58) Field of Classification Search

USPC D19/26, 27, 28, 29, 30

CPC B42D 3/00; B42D 1/00

See application file for complete search history.
